UNITED STATES PATENT OFFICE

113,777

DESIGN FOR A COMBINED PERFUME BOTTLE AND CONTAINER THEREFOR

George Stephenson Worssam, Watford, England,
assignor to Savile Perfumery Limited, Wat-
ford Junction, Watford, England, a British
company

Application April 2, 1938, Serial No. 76,232
In Great Britain June 1, 1937

Term of patent 7 years

To all whom it may concern:

Be it known that I, George Stephenson Wors-
sam, a subject of the King of England, residing
at Crossways, Cassiobury Park Avenue, Wat-
ford, Hertfordshire, England, have invented a
new, original, and ornamental Design for a Com-
bined Perfume Bottle and Container Therefor, of
which the following is a specification, reference
being had to the accompanying drawing, form-
ing part thereof. This application is a continu-
ation-in-part of my prior United States Design
application, Serial No. 72,123 filed October 11,
1937.

In the drawing:

Figure 1 is a side elevational view of the com-
bined perfume bottle and container therefor,
showing my new design;

Figure 2 is a front view thereof;
Figure 3 is a top plan view;
Figure 4 is a bottom or under plan view;
Figure 5 is a perspective view of the assem-
bled bottle and container taken from underneath;
Figure 6 is an exploded view showing the parts
fully separated; and

Figure 7 is a perspective view of the bottle
and its supporting base looking from above and
from the rear.

I claim:

The ornamental design for a combined perfume
bottle and container therefor, as shown.

GEORGE STEPHENSON WORSSAM.
